UNITED STATES PATENT OFFICE.

AUGUSTIN HENTSCHEL, OF BERLIN, GERMANY, ASSIGNOR, BY MESNE ASSIGNMENTS,
TO THE FIRM OF THE HIND & HARRISON PLUSH CO., OF CLARK MILLS, NEW YORK.

GOFFERING-PRESS.

1,070,254.

Specification of Letters Patent.

Patented Aug. 12, 1913.

Application filed February 24, 1910. Serial No. 545,763.

To all whom it may concern:

Be it known that I, AUGUSTIN HENTSCHEL, a subject of the German Emperor, and residing at Berlin, Germany, have invented 5 certain new and useful Improvements in Goffering-Presses, of which the following is a specification.

This invention involves certain improvements in and relating to goffering presses 10 and the like, and the objects and nature of the invention will be readily understood by those skilled in the art in the light of the following explanation of the accompanying drawing illustrating what I now believe to 15 be the preferred mechanical expression or embodiment from among other formations, arrangements and combinations within the spirit and scope of the invention.

My improved apparatus is specially distinguished 20 from goffering machines or like apparatus known heretofore by the peculiar, suitable coöperation of its individual parts and by the provision of means at both ends of the press for transporting the material 25 and keeping it flat before and after it has been goffered.

One illustrative embodiment of my invention is represented by way of example in the accompanying drawing in side elevation.

30 My apparatus comprises, on the one hand, a press having a stationary plate *a* and a vertically movable plate *b*, both of which can be heated and are so large that even quite broad, double widths of goods can be 35 stretched and treated between the same, the press being operated by knee-levers for example. In the illustrative embodiment the bottom plate *b* can be raised and lowered by knee-lever transmission by rotating the shaft 40 *c* by means of two hand levers *d* arranged one at each end of the shaft. On the other hand, my apparatus comprises the goffering tool which consists of a plate-shaped counter-die *e*, and the appertaining matrix *f* pivotally connected at *g* with the former and balanced by a counter-weight *h* secured to one end of two ropes *k* guided over pulleys *i*, the other ends of these ropes being hooked into the side-pieces *l* of the counter-die *e*. 45 At both sides of the bottom plate *b* are secured two rails *m*. In front of the press I arrange a table which is preferably a lattice grid resting on the rails *m* and the supports *n*. At each end of the rails *m* is suspended 50 a roller *p* and *q*, respectively, on each of

which is secured one end of a so-called apron *r* and *s*, respectively, provided at the other end with catches attached to the matrix.

At the two ends of the rollers *p*, *q* are attached grooved pulleys *t*, *u*, respectively, 60 and counter-weights *x*, *y* are respectively secured to the ends of the ropes passing over the guides *v*, *w*.

My new apparatus is used as follows:—At first the material *z* to be goffered, which has 65 been previously moistened and preferably contained in a traveling box *2* at the rear of the apparatus, is passed over roller *q*, apron *s* and between counter-die *e* and matrix *f* to the front end of the latter; plate *e* is then 70 lowered onto matrix *f* and the goffering tool thus charged is pushed between the heated press-plates *a* and *b*.

Owing to the weight of the portion of material *z* between the roller *q* and the 75 top layer of material in the box *2* and to the friction of the material with the apron *s* the portion of the material *z* located rearwardly of the tool is transported and supported back by apron *s* and roller *q*, 80 the latter being rotated in consequence of weight *y* descending. Hence the apron *s* and its tensioning means constitute a transporting means for this rear portion of the material or web *z*. After the goffering tool 85 has been pushed between the plates *a* and *b*, by rotating levers *d* the press is moved and the pattern of the counter-die is impressed in the material *z*. As in most instances, particularly when goffering piled 90 goods, the material is moistened, the steam generated by the heat of plates *a* and *b* has a fixing effect on the pattern. After this action has taken place for a sufficient time, the press is opened by raising levers *d*, the goffering tool is pulled forward and opened by raising the counter-die *e*. The embossed portion of the material *z* lying on matrix *f* is then removed from the same and the material is pulled so far forward that the next 100 part lies on the matrix. The above described operation is then repeated. When the goffering tool is pushed into the press for the second and subsequent times, the previously embossed portion of the fabric, 105 which may be in a box *o* in front of the apparatus, is carried, supported or transported rearwardly on the front apron *r*, which unwinds from roller *p*, and slides over the grid or table, while the rear apron *s*, is simulta-

110

neously being pulled rearwardly by and wound on its roller *q*. When the goffering tool is moved forwardly from the press, the rear apron *s*, is thereby pulled forwardly and 5 is unwound from and against the tension of its roller *q*, while the front apron *r*, is simultaneously pulled forwardly by and is wound on its roller *p*, and hence carries, or supports the embossed portion of the fabric forwardly 10 for deposit in the front box *c*.

It is evident that various changes, variations and modifications might be resorted to without departing from the spirit and scope of my invention as defined by the claims and 15 hence I do not wish to limit myself to the exact disclosures hereof.

What I claim is:—

1. In goffering apparatus, the combination with a press, of a goffering tool movable into and out of said press and adapted 20 to receive the material to be goffered, and means at each side of said press for transporting material extending beyond the goffering tool.

2. In goffering apparatus, the combination with a press, of a goffering tool comprising a matrix and a counterbalanced counter-die pivotally connected therewith, movable into and out of said press and 30 adapted to receive an entire breadth of material to be goffered, and means at each side of said press for transporting material extending beyond the goffering tool.

3. In goffering apparatus, the combination with a press, of a goffering tool movable into and out of said press and adapted 35 to receive material to be goffered, a table in front of said press, and means for transporting material extending beyond the ends of the goffering tool.

4. In goffering apparatus, the combination with a heatable press, of rails through the same, a folding goffering tool movable longitudinally of said rails, rollers at the

ends of said rails, aprons attached to said 45 rollers and to said tool, and means acting on said rollers to rotate the same to wind their aprons thereon.

5. In combination, a press, and a goffering tool movable into and from said press 50 and adapted to goffer successive portions of a length of material, said tool being movable to and from the press in a direction longitudinally of said length of material, said material being movable longitudinally of 55 said tool to present successive portions to the tool and movable longitudinally with the tool as the tool is moved to and from the press, said tool being provided with means moving therewith to support and maintain the material in flat condition while the tool is being moved to and from the press.

6. In combination, a press, and a goffering tool movable into and from said press 60 and adapted to coöperate with said press in goffering successive portions of a length of material, and means movable with said tool to carry and maintain the portions of the material beyond the tool in flat condition.

7. In combination, a press, means coöperating therewith to successively goffer portions of a length of material, and supporting aprons provided with controlling means for portions of said length of material extending beyond said first mentioned means. 70

8. In combination, a press, a goffering tool movable into and from the press and adapted to successively receive and operate on portions of a length of material, and an apron forming an end extension of said tool 75 and provided with automatic winding means.

In testimony whereof, I affix my signature in the presence of two witnesses.

AUGUSTIN HENTSCHEL.
